United States Patent Office

Des. 191,438
Patented Oct. 3, 1961

191,438

EDIFICE

Jehu D. Paulson, 2705 Everett Ave., Raleigh, N.C.

Filed Apr. 20, 1959, Ser. No. 55,575

Term of patent 14 years

(Cl. D13—1)

FIGURE 1

FIGURE 2

FIGURE 3

In the drawings:

FIGURE 1 is a perspective view of an edifice embodying my new design;
FIGURE 2 is a top plan view thereof; and
FIGURE 3 is a side elevational view thereof.
I claim:
The ornamental design for an edifice, as shown.
